(57) **CLAIM**

The ornamental design for a container dome, as shown and described.

DESCRIPTION

FIG. 1 is an enlarged perspective view of a first embodiment of a container dome showing our new design;

FIG. 2 is a reduced front elevation view thereof, the rear, left side, and right side being an identical image;

FIG. 3 is a bottom plan view thereof;

FIG. 4 is an enlarged top plan view thereof;

FIG. 5 is an enlarged perspective view of a second embodiment of a container dome showing our new design;

FIG. 6 is a reduced front elevation view thereof, the rear, left side, and right side being an identical image;

FIG. 7 is a bottom plan view thereof; and,

FIG. 8 is an enlarged top plan view thereof.

Portions of the container shown in broken lines in the figures are for illustrative purposes only and form no part of the claimed design.
